INFORMATIVE BARREL FOR PENCILS,
PENS, OR THE LIKE

Lillian Yancey Huffaker, Los Angeles, Calif.

Application November 30, 1938, Serial No. 243,249

14 Claims. (Cl. 24—95)

This invention relates to a barrel adapted to be combined with a pencil, pen, or any other similar stem-like article, one of the objects of the invention being to provide a barrel having an area through which certain of the contents 5 are visible, simple and compact means being housed within the barrel whereby a rolled web can be moved longitudinally within the barrel for the purpose of displaying any informative 10 data thereon, pictures, or the like or for bringing into position portions of the web which have been marked off to receive scores of games or which are free from printed matter and designed solely to receive notations or memoranda.

15 A further object is to provide web-carrying mechanism which can be operated readily for moving the web in either direction.

A still further object is to provide the barrel with web-carrying means in the form of a cartridge adapted to be supplied as a refill and which can be readily placed in the barrel and coupled to its operating means.

20 A further object is to provide a web-carrying cartridge which, when in position within the barrel, will be completely concealed, the only object appearing through the barrel being that portion of the web which is on display.

Another object is to utilize a cartridge which, if desired, can be employed as a container for 25 a supply of lead if the barrel constitutes a part of a pencil of the type utilizing lead refills.

Another object is to provide an article of this character which can be made of fountain pen size, because of its compact, light and simple 30 construction.

With the foregoing and other objects in view which will appear as the description proceeds, the invention consists of certain novel details of construction and combinations of parts hereinafter more fully described and pointed out in the claims, it being understood that changes may be made in the construction and arrangement of parts without departing from the spirit of the invention as claimed.

40 In the accompanying drawings the preferred form of the invention has been shown.

In said drawings

Figure 1 is a plan view of a pencil on an enlarged scale provided with the present improvements.

45 Figure 2 is a section on line 2—2, Figure 1, the tip portion of the pencil being shown in elevation.

50 Figure 3 is a section through the barrel taken

on a still larger scale, said section being on the line 3—3, Figure 2.

Figure 4 is a section on line 4—4, Figure 2.

Figure 5 is a section on line 5—5, Figure 2.

Figure 6 is a section through the barrel taken 5 on the line 6—6, Figure 5.

Figure 7 is a perspective view of the cartridge from which the spools, web and tie-rods have been removed, a portion of the cartridge being 10 broken away.

Figure 8 is an elevation of a pencil having a barrel differing from that shown in Figure 1.

Figure 9 is a section on line 9—9, Figure 8.

Figure 10 is a section through one end.

Figure 11 is a section showing a modified form. 15

Referring to the figures by characters of reference 1 designates a tubular barrel of any desired proportions and made of any preferred material. For example it can be made of a transparent molded plastic constituting a closed 20 window, as in Figure 8, or it can be made of a non-transparent molded plastic and in either case the barrel can be formed with a window opening 2 extending longitudinally thereof for a distance slightly less than the width of the web 25 used in the barrel and hereinafter described. The transparent barrel or window would of course extend entirely around the pencil but if a window opening is used it would extend partly around the barrel.

30 Each end of the barrel is preferably formed with interior screw-threads as indicated at 3 and 3 respectively and the threads 3 are adapted to be engaged by a closure the nature of which will depend upon the article to which the barrel is applied. If the barrel is to be used with a magazine pencil, this closure can be in the form of a hollow plug 5 adapted to be screwed into the end of the barrel and, if desired, carrying an eraser 6. This plug is cemented or otherwise 35 secured within the body 1 of the magazine pencil, this body carrying a rotatable tip 8 and any suitable pencil mechanism indicated generally at 9 for holding and feeding a lead 10 relative to the top 8. A gasket or washer 11 can be clamped 40 between the body 1 and the end of the barrel as shown for the purpose of forming a tight connection. Obviously other types of closures could be used at this end of the barrel. For example 45 a pen holder, a cane, or in fact anything of a stem-like nature could be employed. Under some conditions it might even be found desirable to close said end of the barrel with an ornamental plug having a knob or the like providing a suitable finish. These modifications are all so ob-

55

vious that it is not deemed necessary to describe or illustrate them in detail inasmuch as none of them constitutes anything more than a closure for one end of the barrel.

5 The other end of the barrel 1 containing the threads 4 is adapted to receive a screw plug 12, there being a recess 13 extending into this screw plug from that end thereof insertible into the barrel, this recess being countersunk as at 14 to 10 provide an interior annular shoulder 15. A disk 16 can be securely held within the countersink 14 where it will bear against shoulder 15 and this disk, together with the outer end of the screw plug, constitutes a bearing for an actuating 15 spindle 17 mounted to slide and rotate therein. To the outer end of this spindle is secured a cap 18 having an annular apron 18' which fits loosely against and surrounds a portion of the screw plug 12 and, when in one extreme position, is 20 adapted to bind upon a washer or gasket 19 extending around the screw plug and bearing against the adjacent end of the barrel 1. This cap 18 constitutes means for sliding and rotating the spindle 17.

25 A pair of stems 20 and 21 are journaled in the disk 16 and the outer end of plug 12. These stems project inwardly beyond the plug and each of them has a blade-like extension 22 or 23 respectively coaxial with the stem. Secured to 30 stem 20 and held thereby close to the end wall of the recess 13 is a gear 24 and another gear 25 is secured to and rotates with stem 21, this latter gear being located adjacent to the disk 16. Another gear 26 is secured to and movable with the 35 spindle 17 and when this spindle has been shifted longitudinally to one position, gear 26 meshes with gear 25 whereas when the spindle is shifted to the other limit of its movement, gear 26 is moved out of mesh with gear 25 and brought 40 into mesh with gear 24.

For the purpose of preventing free rotation of the stems 20 and 21 when their gears are out of mesh, a substantially U-shaped spring 27 is placed astride spindle 17 without contacting with it but 45 the legs of this spring exert a constant outward pressure against the stems 20 and 21.

For use in connection with the structure thus far described, there is provided a removable cartridge for holding the web to be actuated and displayed. This cartridge can be made in various ways but it is preferred to stamp this out of a single blank of sheet metal bent to form disk-like heads 28 connected by an intermediate channelled portion 29 the side walls of which are folded inwardly, as shown at 30. Thus as these side walls are brought together they can cooperate with the channelled member 29 to form a compartment 31 and access to this compartment can be had through an opening 32 in one of the heads 28. If such a compartment is used it can be employed for holding various objects. For example if the barrel is connected to a magazine pencil, this compartment can be used as a holder for a supply of leads. If it is not intended to provide a compartment 31, the structure can be lightened by shortening the inturned sides so that they will not come close together as shown.

The outer or convex surface of the channelled member 29 constitutes a platen or guide as hereinafter explained and formed in the heads at 70 points beyond this platen are openings 33. The corresponding openings in the two heads are coaxial and are also positioned to aline with the stems 20 and 21 when the cartridge is inserted in the barrel. These openings are adapted to receive the reduced ends 34 and 35 of slender

spools 36 each of which is preferably formed with a longitudinal slot 37 for receiving the ends of a web 38 as shown particularly in Figure 3. The reduced ends 35 are formed with V-shaped recesses 39 and the opposed walls of each recess converge downwardly to the side walls of a short slot 40 extending into the adjacent portion of the spool and diametrically thereacross. Each slot 40 is proportioned to receive one of the extensions 22 or 23 when the cartridge is inserted longitudinally in the barrel.

For the purpose of reenforcing the cartridge, stiffening or reenforcing rods 41 can be secured at its ends within openings 42 provided at suitable points in the heads 28. It is preferred to locate 15 two of these rods within the side portions of the slots 39 while a third one can be located adjacent to and between the openings 33. Thus they will at no time interfere with the placing or operation 20 of the web 38.

It is to be understood that any desired number of cartridges can be used successively within the barrel. Each cartridge is supplied with a web which is rolled on one of the spools 36 and attached to both of them at its respective ends. 25 The outer surface of the web can be blank if it is desired to enter memoranda thereon or it can be formed with outlined spaces for receiving scores of games. On other webs there can be a display of any suitable printed matter such as 30 text, pictures, road maps, etc. In fact the web used in the barrel can be for various purposes.

When it is desired to use in the barrel a cartridge having a selected kind of web, the closure 5 is disengaged from the thread 3 at one end of the barrel. The selected cartridge is then inserted longitudinally in the barrel, the ends 35 containing recesses 39 being extended toward the plug 12.

As the cartridge reaches its extreme position, the slot extensions 22 and 23 are guided by the inclined walls of recesses 39 so that the stems 20 and 21 will rotate until these extensions can enter slots 40. Thus the two spools will be coupled to the respective stems 20 and 21. Thereafter the closure 5 can be reinserted and the device is ready for use. When the cartridge is properly located the platen 29 will serve as a guide for the web and if it is used in a barrel having a window opening 2, it will extend throughout the length and width of the opening. All portions of the web between the spools will be exposed if the window is in the form of a transparent barrel, as in Figure 8. If a window opening 2 is used, the web surface exposed therethrough can receive any suitable memoranda such as notes, scores, etc. If the window is a transparent portion of an opaque barrel, any text matter, pictures, etc., appearing on that portion of the web supported by the platen 29, will be legible through the window. When it is desired to shift the web so as to bring an unexposed portion into view, the cap 18 is shifted longitudinally so as to bring its gear 26 into mesh with the gear 24 or 25 coupled to the spool on which the web is to be wound. Following the shifting of gear 26 to its correct position, the cap 18 is rotated in such a direction as to cause the coupled spool to wind the web thereon and as it thus winds the web and at the same time unwinds it from the other spool, the latter spool will be held against free rotation because of the pressure of spring 27 against its gear-carrying stem.

Should it be desired at any time to reverse the rotation of the web, it is merely necessary to shift the cap 18 to its other extreme position, thus coupling gear 26 with the other stem gear where- 70

upon, when the cap is rotated, the movement of the web will be reversed.

Although it has been explained that the cartridge is adapted to be inserted and removed through that end which is normally closed by the plug 5, it is to be understood that it could also be inserted or removed from the other end simply by removing the screw plug 12 from the barrel.

10 In the form of the invention illustrated in Figures 8, 9 and 10, the cap 41, which corresponds with cap 18, can be made with an apron 42 of such length as to lap the end of the transparent barrel.

15 An important advantage resulting from the use of a barrel all portions of which are transparent, is that a greater area of the surface of the web is exposed at one time. The rolled ends of the web are substantially in contact at all times so that 20 the web is exposed to view throughout the greater portion of the circumference of the barrel.

As has before been stated the sides of the platen need not come together. Instead they can be spaced apart as shown at 43 in Figures 9 and 11.

25 Furthermore it is not always necessary to use the reinforcing rods which have been shown at 41.

Instead of providing the barrel with an opening through which the web is exposed, as shown in Figures 1 to 3 inclusive, a magnifying or reading glass 44 can be used to close the opening and at the same time magnify the matter thereunder displayed on the web.

What is claimed is:

1. The combination with a barrel providing a 35 window, of a cartridge removably mounted in the barrel, separate spools carried thereby, and detachable means separate from the cartridge for actuating the spools, said means including a structure removably engaging the barrel, a shiftable gear carried by and rotatably mounted relative to said structure, means for operating the gear, and separate means actuated by said gear for detachably engaging and driving either of the spools.

45 2. The combination with a barrel providing a window, of a cartridge removably mounted in the barrel and including heads and a combined web guide and platen connecting the heads, said platen being positioned adjacent to the wall of the 50 barrel, separate spools journaled in the heads for engagement by the ends of a web slidably mounted on the platen, a cap slidably and rotatably mounted relative to the barrel, and selective means controlled by the cap for rotating either of the spools.

55 3. The combination with a barrel providing a window, of a cartridge removably mounted in the barrel and including heads and a combined web guide and platen connecting the heads, said platen being positioned adjacent to the wall of the barrel window, separate spools journaled in the heads for engagement by the ends of a web slidably mounted on the platen, a cap slidably and rotatably mounted relative to the barrel, and selective means controlled by the cap for rotating the spools separately in opposite directions respectively.

4. The combination with a barrel, of a cartridge removably mounted within the barrel and including a platen, heads at the ends thereof, spools mounted for rotation within the heads for engagement with the ends of a web extending across the platen, driving stems detachably engaging the respective spools, an operating element 70 slidably and rotatably mounted relative to the barrel and connected thereto, and means controlled by said operating means for rotating the respective stems and spools in opposite directions respectively.

the barrel and connected thereto, and means controlled by said operating means for rotating the respective stems and spools in opposite directions respectively.

5. The combination with a barrel, of a cartridge 5 removably mounted within the barrel and including a platen, heads at the ends thereof, spools mounted for rotation within the heads for engagement with the ends of a web extending across the platen, driving stems detachably engaging 10 the respective spools, an operating element slidably and rotatably mounted relative to the barrel and connected thereto, and means controlled by said operating means for rotating the respective stems and spools in opposite directions 15 respectively, said means including non-aligned gears on the respective stems, a spindle slidable and rotatable with the operating means, and a gear shiftable with the spindle into mesh with either of the first named gears. 20

6. The combination with a barrel, of a cartridge removably mounted within the barrel and including a platen, heads at the ends thereof, spools mounted for rotation within the heads for engagement with the ends of a web extending 25 across the platen, driving stems detachably engaging the respective spools, an operating element slidably and rotatably mounted relative to the barrel and connected thereto, and means controlled by said operating means for rotating the 30 respective stems and spools in opposite directions respectively, said means including non-aligned gears on the respective stems, a spindle slidable and rotatable with the operating means, and a gear shiftable with the spindle into mesh with either of the first named gears, and friction means for retarding the rotation of the stems. 35

7. The combination with a barrel, of a cartridge insertible longitudinally into the barrel and comprising heads and a platen connecting 40 the heads, said platen being positioned adjacent to the wall of the barrel, spools journaled within the heads for connection to the ends of a web extending across the platen, either of said spools constituting means for winding the web thereon 45 off of the other spool, means closing the ends of the barrel for holding the cartridge against displacement longitudinally, and changeable driving mechanism carried by one of said means for rotating the spools separately in opposite directions 50 respectively, each spool, when actuated by said means, constituting means for transmitting motion through the engaged web to the other spool.

8. The combination with a barrel, of a cartridge therein including a platen, separate spools 55 rotatably mounted adjacent to the platen and carried by the cartridge, each of said spools constituting means for engaging one end of a web and winding it thereon, said platen constituting a support for a portion of the web between the 60 spools, an operating spindle slidably and rotatably connected to the barrel, and separate means separately actuated by said spindle for transmitting motion directly but separately to the respective spools, each spool, when actuated, constituting means for transmitting motion through the engaged web to the other spool, and a closure for one end of the barrel. 65

9. The combination with a barrel, of a cartridge removably mounted in the barrel and including a platen constituting a guide, spaced web-engaging rolls, and bearings for the rolls at opposite ends of the platen, a closure for one end of the barrel, separate stems mounted for rotation in the closure and for sliding engagement 70

75

with the respective spools, said stems and spools cooperating to transmit motion from one to the other, a spindle slidably and rotatably mounted in the closure, means for sliding and rotating the spindle, non-aligning gears on the respective stems and rotatable therewith, and a gear secured to the spindle and between the gears, said spindle being shiftable to move its gear into mesh with either of the gears on the stem.

10. The combination with a barrel, a closure for one end thereof, stems projecting from the closure and rotatably mounted therein, and shiftable operating means for rotating the stems in opposite directions respectively and independently, of a cartridge including a platen, spools rotatably mounted in the cartridge for engagement with the ends of a web extending across the platen, each of said spools having a slotted end, said cartridge being insertable longitudinally 15 into the barrel to couple the slotted ends of the spools to the respective stems and to position the platen adjacent to the wall of the barrel.

11. The combination with a barrel for attachment at one end to an article of utility, of a closure for the other end of the barrel, a spindle slidably and rotatably mounted in the closure, means outside of the closure for actuating the spindle, stems rotatably mounted within and projecting into the barrel from the closure, means operated 20 by the spindle when rotated while in one extreme position for rotating one of the stems in one di-

rection, means operated by the stem when rotated in the same direction while in its other extreme position for rotating the other stem in the opposite direction, a web within the barrel, means for supporting a portion of the web close to the 5 wall of the barrel, and means detachably engaged by the ends of the web for winding said web, said means being detachably coupled to the respective stems.

12. The combination with a barrel having a 10 window, of a cartridge in the barrel including a platen adjacent to the window, heads thereon, and web-engaging spools journaled in the heads, each of said spools having a slot extending into one end thereof. 15

13. The combination with a barrel having a window, of a cartridge in the barrel including a platen adjacent to the window, heads thereon, and web-engaging spools journaled in the heads, each of said spools having a slot extending into 20 one end thereof, the outer end of each slot being flared to provide deflecting surfaces.

14. The combination with a barrel having a window, of a cartridge in the barrel including a platen adjacent to the window, heads thereon, 25 and web-engaging spools journaled in the heads, each of said spools having a slot extending into one end thereof, and reinforcing connections between the heads.

30 LILLIAN YANCEY HUFFAKER.
